Primary Examiner — Kelley Donnelly(74) *Attorney, Agent, or Firm* — Weiss & Arons LLP(57) **CLAIM**

The ornamental design for a modular closet section, as shown and described.

DESCRIPTION

FIG. 1 is a top, front, left perspective view of a modular closet section showing my new design;
FIG. 2 is a front view thereof;
FIG. 3 is a rear view thereof;
FIG. 4 is a right side view thereof;
FIG. 5 is a left side view thereof;
FIG. 6 is a top view thereof;
FIG. 7 is a bottom view thereof;
FIG. 8 is bottom, front, left perspective view thereof;
FIG. 9 is a top, back, right perspective view thereof; and,
FIG. 10 is a bottom, back, right perspective view thereof. The broken line showing of the environment is for illustrative purposes only and forms no part of the claimed design.
